VENTILATING WINDOW SHADE

Filed March 5, 1931.

UNITED STATES PATENT OFFICE

LOUIS A. ROSS, OF NEWARK, NEW JERSEY

VENTILATING WINDOW SHADE

Application filed March 5, 1931. Serial No. 520,298.

This invention relates in general to window shades, and more particularly to window shades which are mounted upon spring-operated rollers.

5 One object of the invention is to provide a window shade embodying novel and improved features of construction whereby air may pass through the shade for ventilating purposes and so as to avoid rattling or flapping of the shade when it is drawn over a partially open window.

Another object is to provide a window shade of this character having a plurality of openings therethrough to permit the passage 15 of air to and from a room through a window to which the shade is applied, and novel and improved means for concealing the openings and directing incoming air downwardly from the openings.

20 Other objects are to provide such a window shade having one or more horizontal rows of openings and a flap or closure secured to the side of the shade which faces into the room when the shade is applied to a window, said 25 flap being movable relatively to the shade to permit ingress and egress of air through the openings; to provide a novel and improved form of flap or closure for the openings in the shade; to provide such a shade which 30 shall be simple and inexpensive in construction and which shall in no way hinder rolling and unrolling of the shade upon the spring roller, and to obtain other advantages and results as will be brought out in the following description.

35 Referring to the accompanying drawings, in which corresponding and like parts are designated throughout the several views by the same reference characters,

40 Figure 1 is an inside elevation of a window having a shade embodying my invention applied thereto and shown in operation;

45 Figure 2 is a transverse vertical sectional view through the shade showing the flap or closure for the opening partially closed;

Figure 3 is a similar view showing the flap in open position;

50 Figure 4 is a horizontal sectional view, on the line 4-4 of Figure 2;

Figure 5 is a similar view, on the line 5-5 of Figure 3, and

Figure 6 is a view similar to Figure 1 showing a modified form of the invention.

Specifically describing the embodiment of 55 the invention illustrated in Figures 1 to 5, inclusive, the reference character A designates a window frame of known construction which has a known type of shade roller 1 journaled at the top and on the inside thereof. Mounted upon this roller in the usual way is a window shade 2 which has a plurality of horizontal rows of openings 3 therein which are disposed longitudinally of the shade so as to be located at a point adjacent 60 the top of the window when the shade is fully drawn over the window, as shown in Figure 1 of the drawings.

65 Mounted on the inside of the shade to overlie and conceal said openings 3 is a flap or closure 4 formed of suitable flexible material. This flap is secured at one edge to the shade above the openings 3 in any suitable manner as by a line of stitching 5, and the lower edge of the flap is free from the shade. 70 The flap also includes flexible or somewhat resilient end walls 6 which are preferably integral with the body of the flap and are secured at one edge to the shade at the sides thereof, as indicated at 7. These end walls 75 are approximately triangular in shape, and are folded substantially midway of their length, as at 8, so as to collapse flat against the shade beneath the main portion of the flap, as shown in Figures 1 and 2 of the drawings, or to unfold outwardly as the main portion of the flap moves away from the shade, as shown in Figure 3 of the drawings. These 80 end walls serve to securely connect the flap to the shade and to limit outward swinging of the flap away from the shade. They also tend to hold the main portion of the flap in slightly spaced relation to the shade to permit passage of air through the openings 3 at 85 all times, and restrain flying and rattling of the flap.

90 With this construction, it will be observed that when the shade is fully drawn over the window, the flap 4 faces inwardly of the room and entirely conceals the openings 3. 95 100

Upon heavy drafts of air inwardly through the openings 3 from the window, the flap is forced away from the shade by the air, as shown in Figure 3 of the drawings to provide free passage for the air through the shade and thereby ensure adequate ventilation and prevent flapping or rattling of the shade. Outgoing drafts of air may pass upwardly between the flap and the shade through the openings 3. The upper end of the flap being secured to the shade and the lower edge being free, the flap inclines downwardly from the shade and directs currents of air downwardly. When the shade is rolled upwardly on the roller, the end walls 6 fold or collapse toward the shade beneath the main portion of the flap, as shown in Figures 1 and 2 of the drawings, so that the flap causes no hindrance to the rolling of the shade.

20 A modification of the invention is shown in Figure 6 of the drawings where a shade roller 9 is connected to the lower end of the window frame and the shade is drawn over the window toward the upper end. With this form of the invention the openings 10 corresponding to the openings 3 are formed adjacent the free end of the shade so as to be located at the top of the window when the shade is drawn. Over these openings 10 is secured to the shade a flap 11 identical in construction with the flap 4 shown in Figures 1 to 5, inclusive. The construction and operation of this form of the invention is otherwise the same as that hereinbefore described.

30 It will be observed that in both forms of the invention, due to the cover flap being on the inside of the shade and the bending of the flap as the shade is wound on the roller, the flap will normally tend to swing at its lower edge away from the shade so as to permit free passage of air outwardly through the openings.

35 While I have shown and described the invention as embodied in certain details of construction, it should be understood that this is primarily for the purpose of illustrating the principles of the invention, and that many modifications and changes may be made by those skilled in the art in the details of construction of the invention without departing from the spirit or scope thereof. I am aware of Patents No. 618,441, dated January 31, 1899, and No. 1,630,344, dated May 31, 1927, and do not desire to be understood as attempting to claim constructions such as those shown thereby. Obviously, the ventilating openings and flap closure also may be arranged on the shade so as to be located at the bottom of the window when the shade is drawn, and the transverse edge of the flap may be secured to the shade below the openings instead of above the openings.

40 Having thus described the invention, what I claim is:

45 1. A window shade having a plurality of

openings therethrough for passage of air, a cover flap for said openings secured at one edge transverse of the shade, the other edge of said flap being free, and means for securing the ends of the flap to the shade to induce and limit movement of said cover flap away from the shade so as to admit air through said openings and prevent complete uncovering of said opening by the flap.

2. A window shade having a plurality of openings therethrough for passage of air, a cover flap for said openings having a main portion to overlie said openings and secured at one edge transversely of the shade, and walls at the ends of said main portion secured to said shade foldable beneath the flap and tending normally to swing said flap away from the shade, whereby movement of said flap away from the shade is permitted by extension of said end walls to admit air through said openings, said movement of the flap is limited by said end walls, and said end walls may fold between said main portion and said shade to permit movement of the flap toward said shade.
